Att'y:

UNITED STATES PATENT OFFICE.

HERBERT S. HUMPHREY, OF KALAMAZOO, MICHIGAN.

DESIGN FOR A GAS-STOVE.

No. 37,669.

Specification for Design.

Patented Nov. 14, 1905.

Application filed September 13, 1905. Serial No. 278,350. Term of patent 14 years.

To all whom it may concern:

Be it known that I, HERBERT S. HUMPHREY, a citizen of the United States, residing at the city of Kalamazoo, in the county of Kalamazoo and State of Michigan, have invented a new, original, and ornamental Design for a Gas-Stove.

My new, original, and ornamental design for a gas-stove is clearly illustrated in the accompanying drawings, in which—

Figure 1 is a plan, and Fig. 2 is an elevation, thereof.

I claim—

The ornamental design for a gas-stove, as shown.

HERBERT S. HUMPHREY.
